TOY BIRD FIGURE

Aubrey Greene, 29 Cooper Road,
Scarsdale, N.Y. 10583

Filed July 22, 1969, Ser. No. 18,292

Term of patent 14 years

Int. Cl. D21—02

U.S. Cl. D34—2

FIG. 1

FIG. 2

FIG. 3

FIG. 1 is a front view in elevation of a toy bird figure showing my new design;

FIG. 2 is a side view in elevation thereof taken at one side, the opposite side being substantially the same;

FIG. 3 is a reduced rear view in elevation thereof; and

FIG. 4 is a bottom plan view of the new design.

I claim:

The ornamental design for a toy bird figure, substantially as shown and described.
